C. F. MACDONALD.
VEHICLE HEADLIGHT.
APPLICATION FILED JAN. 21, 1916.

1,198,466.

Patented Sept. 19, 1916.

UNITED STATES PATENT OFFICE.

CLAYTON F. MACDONALD, OF CLEVELAND, OHIO.

VEHICLE-HEADLIGHT.

1,198,466.

Specification of Letters Patent. Patented Sept. 19, 1916:

Application filed January 21, 1916. Serial No. 73,345.

To all whom it may concern:

Be it known that I, CLAYTON F. MACDONALD, a citizen of the United States, residing at Cleveland, in the county of Cuyahoga and State of Ohio, have invented certain new and useful Improvements in Vehicle-Headlights, of which the following is a specification.

My invention relates to vehicle headlights, and comprises an improved means for tilting the reflector in the headlight, whereby the beam of light may be directed either straight ahead or downwardly or upwardly to meet varying needs. This improved means is operable and controllable preferably by electrical instrumentalities, including an electric switch located at the steering wheel or seat of the driver of the vehicle, and the device is also capable of being manipulated by a finger-gripping device arranged at the side of each lamp or headlight.

In the accompanying drawings, Figure 1 is a sectional view of a headlight embodying my improvement, and Fig. 2 is a similar view showing the reflector tilted to direct the beam of light upwardly. Fig. 3 is a plan view and section on substantially the horizontal center of Fig. 1, and Fig. 4 is a cross section and rear elevation on line 4—4, Fig. 1.

The head-light or lamp comprises a shell or casing 2 having a cover or door 3 at its front adapted to be removed or opened and carrying the usual lens or plate of glass 4. A parabolic reflector 5 is pivotally supported within casing 2 by pivot pins or screws 6, located preferably opposite one another on the horizontal diagonal line of the casing and removably mounted in the annular flange 7 at the front end of said casing so that the reflector and interior working parts may be conveniently assembled and disassembled. The reflector carries the usual electric light 8 in a socket 9 at its center and rear, and the space in the casing behind the reflector is utilized to house my improved mechanism for tilting the reflector. This mechanism consists of a ratchet wheel 10 mounted on a rotatable shaft 11 having bearing in a standard 12 affixed to the bottom at one side of the vertical center of casing 2 and the said shaft extends through one side of the casing, see Fig. 4, and has a head or finger gripping member 14 at its end whereby the ratchet-wheel may be turned

and set in any predetermined position. A short crank rod 15 is pivotally connected at its opposite ends to ratchet wheel 10 and a lug or ear 16 at the bottom of reflector 5, whereby any rotative movement of the ratchet wheel will cause a corresponding tilting of the reflector. A stop pawl 17 pivotally mounted upon standard 12 engages the top of ratchet wheel 10, and a coiled spring 18 connected with the reflector and an adjusting and fastening screw 19 at the bottom of casing 2 provides a constant pull on crank rod 15 to hold the ratchet teeth of wheel 10 in stop engagement with pawl 17, and the spring also takes up all looseness of the parts and prevents noise and rattle. There is also a time when the spring rotates the ratchet wheel a full one-half of a revolution without stop or intermission and that is when the crank rod 15 is carried across the dead center of said wheel on an upward movement thereof, thereby tilting the reflector instantly from one extreme position (downwardly inclined) to another extreme position (upwardly inclined), as delineated in dotted lines, Fig. 1, and full lines Fig. 2. On the other hand when the reflector is tilted upwardly as shown in Fig. 2, a step-by-step rotation of ratchet wheel 10 will tilt the reflector step by step, the number and degree of the inclined positions assumed by the reflector being dependent upon the number of ratchet teeth and radial movements of wheel 10 as it rotates intermittently throughout one-half of a revolution carrying the crank rod to the right from the starting position shown in Fig. 2. Working the present ratchet wheel in this way, an advance of one tooth will lower the beam of light slightly but it will still be projected upwardly. The advance of a second tooth will place the reflector in a central position as shown in full lines, Fig. 1 and project the beam of light straight ahead. The next tooth advanced will tilt the reflector to direct the light downwardly, and a further movement of one tooth of wheel 10 will augment this downward tilting and place the reflector and its crank rod in the position shown in dotted lines, Fig. 1. This latter position places the crank rod slightly below the dead center of thrust; therefore, further rotation of wheel 10 will carry the crank pin across

the dead center and the pull of spring 18 is then exercised to rotate wheel 10 approximately one-half of a revolution to place the reflector in the inclined position 5 shown in Fig. 2.

The instrumentalities for imparting an intermittent movement to ratchet wheel 10 comprise an arm 20 mounted to oscillate upon shaft 11 at one side of said wheel and 10 provided with a spring-pressed dog 21 to engage the ratchet teeth, the free end of said arm having loose pivotal engagement or linked connection with the lower end of the movable core 22 of an electric magnet 23 15 mounted upon standard 12. The coil of this magnet is connected in a battery circuit 24 having a suitable switch 25 to close the same, and when the coil is energized the core is lifted and the ratchet wheel rotated 20 the distance of one tooth. In this way the operator of the vehicle may change the position of the reflector instantly to throw the beam of light variously as required, as upward in hill climbing and reading elevated 25 signs, or straight ahead for throwing the beam of light the maximum distance ahead on a level with the road, or downward in different degree for dimming purposes, that is to remove the flaring effects of the horizontal beam of light. Two head-lights are 30 used generally, and these may be operated independently or jointly, dependent upon the manner in which the electrical connections are made as must be obvious to those 35 skilled in the electrical art. For example, each magnet coil may be electrically connected in a separate circuit or in series in the same battery circuit. The handle member 14 also permits independent operation 40 and setting, a matter of convenience when the driver happens to be on the ground at the front of the machine, and of advantage when the electrical circuit is out of working order.

45 What I claim is:

1. A head-light casing, a reflector mounted to tilt within said casing, crank and ratchet mechanism and a spring to tilt said reflector, and electrical instrumentalities to 50 operate said mechanism intermittently.

2. A head-light casing and a tilting reflector therein, and ratchet mechanism having an operating shaft extending through said casing and a crank connection with 55 said reflector.

3. In a head-light, a tilting reflector, ratchet mechanism having an operating shaft for manual control and a crank connection with said reflector, and auxiliary

electrical operating means for said ratchet mechanism having a controlling switch.

4. In a head-light, a tilting reflector, a ratchet wheel, a rod connected in crank relations with said wheel and engaged with said reflector to tilt the same, a stop pawl 65 and a spring to co-act with said wheel in tilting and setting said reflector, and means to operate said ratchet wheel and crank connections.

5. In a head-light, a tilting reflector, a ratchet wheel and crank connections and a 70 spring to tilt said reflector, and an electrical power device and associate mechanism to rotate said ratchet wheel intermittently, in combination with an electrical circuit and 75 means to energize said electrical device.

6. In a head-light, a tilting reflector, a spring, a crank and ratchet wheel having operating connections with said reflector, and an electrical magnet having a movable 80 core and a ratchet wheel engaging member to rotate said wheel intermittently.

7. A head-light having a main reflector on horizontal pivots, mechanism to tilt and set said reflector in variable fixed positions 85 to project the full beam of light upwardly or downwardly or horizontally, and electrical actuating means to operate said mechanism.

8. A head-light having a main reflector, crank-mechanism to tilt said reflector in a step by step movement and electrical means to actuate said mechanism.

9. A head-light having a main reflector adapted to tilt on fixed side pivots and a lamp fixed to tilt therewith, ratchet mechanism to tilt said reflector to variable set positions and electrical means to operate 95 said mechanism.

10. A head-light having a main reflector supported on opposite pivots, crank and ratchet wheel mechanism and a connecting rod between said parts and said reflector to tilt the reflector, and electrical means to operate said mechanism having a controlling switch.

11. A head-light casing and a tilting main reflector mounted therein on side pivots at its front, crank and ratchet mechanism and a spring adapted to tilt said reflector on said pivots, in combination with electrical means to operate said mechanism.

In testimony whereof I affix my signature in presence of two witnesses.

CLAYTON F. MACDONALD,

Witnesses:

R. B. Moser,

GEO. E. KRECKER.
